CLAIM

The ornamental design for a collapsible air pump fluid applicator, as shown.

DESCRIPTION

FIG. 1 is a front elevational view of the collapsible air pump fluid applicator of the present invention;

FIG. 2 is a back elevational view of the collapsible air pump fluid applicator of FIG. 1;

FIG. 3 is a left side elevational view of the collapsible air pump fluid applicator of FIG. 1;

FIG. 4 is a right side elevational view of the collapsible air pump fluid applicator of FIG. 1;

FIG. 5 is an enlarged scale top plan view of the collapsible air pump fluid applicator of FIG. 1; and,

FIG. 6 is an enlarged scale bottom plan view of the collapsible air pump fluid applicator of FIG. 1.
